STORM DOOR FRAME

Rexford J. Damiani, Port Washington, N.Y., assignor to Karey Products Corporation, Plainview, N.Y., a corporation of New York

Filed June 18, 1964, Ser. No. 80,459

Term of patent 14 years

(Cl. D13—1)

FIG. 1

FIG. 2

FIG. 3

FIG. 1 is a front elevation of the storm door frame showing my new design,

FIG. 2 is an end view,

FIG. 3 is a rear view, and

FIG. 4 is a cross section taken along lines 4—4 of FIG. 1.

I claim:

The ornamental design for a storm door frame, substantially as shown.
